US0D1008264S

(12) **United States Design Patent** (10) **Patent No.:** **US D1,008,264 S**
(45) **Date of Patent:** **** Dec. 19, 2023**

(54) **PORTABLE MONITOR**

(71) Applicant: **Riying Ma**, Shenzhen (CN)

(72) Inventor: **Riying Ma**, Shenzhen (CN)

(**) Term: **15 Years**

(21) Appl. No.: **29/910,706**

(22) Filed: **Aug. 23, 2023**

(51) LOC (14) Cl. **14-02**

(52) U.S. Cl.

USPC **D14/371**

(58) **Field of Classification Search**

USPC ..... D14/125-127, 138 AB, 305, 307,
D14/315-327, 333-342, 345, 371-379,

(57) **CLAIM**

The ornamental design for a portable monitor, as shown and described.

DESCRIPTION

FIG. 1 is a perspective view of a portable monitor showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the portable monitor, shown in a closed configuration;

FIG. 10 is an enlarged view of portion 10 shown in FIG. 1; and,

FIG. 11 is an enlarged view of portion 11 shown in FIG. 2. The dash-dash broken lines in the drawings depict portions of the portable monitor that form no part of the claimed design.

The dot-dash broken lines represent boundaries of the enlarged portions and form no part of the claimed design.

1 Claim, 11 Drawing Sheets
